UNITED STATES PATENT OFFICE.

STEPHEN G. GERLACH, OF BANTAM, CONNECTICUT.

BURGLAR-ALARM.

1,122,905.

Specification of Letters Patent. Patented Dec. 29, 1914.

Application filed April 17, 1914. Serial No. 832,638.

To all whom it may concern:

Be it known that I, STEPHEN G. GERLACH, a citizen of the United States, residing at Bantam, in the county of Litchfield and 5 State of Connecticut, have invented new and useful Improvements in Burglar Alarms, of which the following is a specification.

The general object of this invention is to 10 announce the unlawful tampering with the lock of a door or the like, by a noise producing element, which is adapted to be operated by the actuation of the lock. And to these ends the invention consists of a casing and a 15 firing pin, and arranging the casing so as to receive the firing pin, in securing a means to the spindle of the lock and arranging the same for engaging the firing pin, so that upon the turning of the spindle the firing 20 pin will be actuated.

Other objects will appear and be better understood from that embodiment of my invention of which the following is a specification, reference being had to the accompanying drawings forming part hereof, in 25 which:—

Figure 1 is a perspective view of my improved lock, Fig. 2 is a side elevational view of the lock having a portion of the front 30 broken away for the sake of clearness, and Fig. 3 is a detail perspective view of a portion of the trigger and firing pin.

As shown in the drawings, 5 indicates a lock-casing, 6 a firing pin, 7 a spring for actuating the firing pin and 8 a trigger piece mounted on the lock spindle 9 and arranged for engagement with the firing pin.

The lock casing may be any of usual 40 structure and formed of any suitable metal such as iron, bronze or the like. At one side of the interior thereof, the casing is provided with a pair of depending lugs 10—10 which are bored so as to slidably receive the rod 6; and located between these lugs 45 and preferably formed integral with the casing, is a ledge 11, whose function will be presently described. At one end thereof, the casing is also provided with an enlarged or solid portion 12, which is provided with 50 bore 13. This bore is in axial alinement with the rod 6, and is of suitable caliber so as to receive a blank cartridge 14 as shown, and for the purpose of providing finger room for inserting a cartridge in the bore

13, or removing a fired cartridge the casing 55 is cut away as indicated at 15.

The rod 6 is slidably fitted in the lugs 10—10 and is adapted to operate as a firing-pin for the cartridge 14, by virtue of the spring 7 projecting the firing-pin there- 60 against. The spring 7 is wound around the firing-pin and is located between the lugs 10, and in order to retain the spring in position, a cross-piece 16 is provided on the firing pin as shown. This cross-piece is 65 adapted to operate as a cocking-piece for the firing-pin, for it will be seen that as the firing-pin is drawn backwardly or away from the cartridge, the cocking-piece may be engaged by the ledge 11, upon a slight 70 turn being given to the firing-pin; and by virtue of the spring being compressed between the lug 10 and the cocking piece, the firing pin may be held in substantially fixed 75 position. At the rear end thereof, the firing-pin is provided with an angularly disposed portion 17, which operates as a sear for the firing-pin, as will be hereafter described, and for the purpose of permitting the free action of this portion 17, the casing 80 of the lock is cut away as shown at 18.

The trigger-piece 8 may be made of any suitable material, and for the purpose of being fixedly positioned on the spindle 9 of the door knob, an annular opening 19 is 85 provided for the reception of the spindle; thus it will be seen that as the spindle is turned in either direction the trigger-piece is rotated in unison therewith. The upper end of the trigger-piece is provided with a 90 substantially V-shaped cut-away portion, which is adapted to receive the portion 17 of the firing pin, when the latter is in the cocked position as shown in Figs. 1 and 3. By virtue of this cut-away portion, having 95 oblique sides, it will be seen that as the trigger piece is rotated by the spindle, these oblique sides tend to cam the portion 17 upwardly, as shown in Fig. 2 and in dotted lines in Fig. 3. Now, as the sear portion is 100 being cammed upwardly, it is obvious, that the firing-pin will be rotated in a lateral direction, thus disengaging the cocking-piece from contacting with the ledge 11, whereupon the spring, being released will 105 project the firing-pin against the cartridge and explode the same.

It is obvious that those skilled in the art

may vary the details of construction and arrangement of parts without departing from the spirit of my invention and therefore I do not wish to be limited to such features except as may be required by the claims.

What I claim as new is:

1. In combination with a lock casing provided with bearings, a knob spindle and having one end adapted to receive a noise-producing element, and a firing-pin slidably mounted in the said bearings, the said firing-pin having one end provided with an angularly disposed portion, means for projecting the firing-pin against the noise-producing element, and means mounted on the knob spindle of the lock-casing and arranged for engaging with the angularly disposed portion of the firing-pin for the purposes set forth.
2. In combination with a lock casing provided with bearings, a knob spindle and

having one end adapted to receive a noise-producing element, and a firing-pin slidably mounted in the bearings and adapted to engage with the noise-producing element, the 25 said firing-pin being provided with an angularly disposed portion, means for directing the firing-pin against the noise-producing element, means mounted on the firing-pin and arranged for engagement with the 30 lock-casing for holding the firing-pin out of operative engagement with the noise-producing element, and means mounted on the knob-spindle and arranged for engaging with the angularly disposed portion of the 35 firing-pin for the purposes set forth.

In testimony whereof I affix my signature in presence of two witnesses.

STEPHEN G. GERLACH.
